(57) **CLAIM**

I claim the ornamental design for a cartridge for aerosol generating device, as shown and described.

DESCRIPTION

FIG. 1 is a first perspective view of a cartridge for aerosol generating device.

FIG. 2 is a second perspective view of the cartridge for aerosol generating device depicted in FIG. 1.

FIG. 3 is a first side view of the cartridge for aerosol generating device depicted in FIG. 1.

FIG. 4 is a second side view of the cartridge for aerosol generating device depicted in FIG. 1.

FIG. 5 is a third side view of the cartridge for aerosol generating device depicted in FIG. 1.

FIG. 6 is a first end perspective view of the cartridge for aerosol generating device depicted in FIG. 1.

FIG. 7 is a second end perspective view of the cartridge for aerosol generating device depicted in FIG. 1; and,

FIG. 8 is a cross-sectional view of the cartridge for aerosol generating device taken on line 8-8 of FIG. 3.

The broken lines in the drawings illustrate portions of the cartridge for aerosol generating device that form no part of the claimed design and depict environmental subject matter only.
